UNITED STATES PATENT OFFICE.

ANSON J. BENTLEY, OF NILES, OHIO.

ICE-MAKING APPARATUS.

Application filed November 8, 1919. Serial No. 336,558.

To all whom it may concern:

Be it known that I, ANSON J. BENTLEY, a citizen of the United States, and a resident of the city of Niles, county of Trumbull, and 5 State of Ohio, have invented an Improvement in Ice-Making Apparatus, of which the following is a specification.

This invention relates to apparatus employed in the manufacture of artificial ice 10 and it particularly relates to the freezing cans which receive water to be frozen and which are placed in or near a freezing solution.

One of the objects of this invention is to 15 provide a fluid conductor to be assembled with the freezing can; the conductor, preferably a tube, will form a conduit for the fluid, generally air under pressure, to the bottom of the freezing can. The fluid after 20 passing into the can will rise and thereby keep the impurities in the water agitated so that they will not be included in the ice.

Another and important object of this invention is to assemble the tube with the 25 freezing can so that the tube does not enter the can thereby avoiding all injury to the tube and its holding means during the formation of the ice and the removal of the ice cake.

30 This invention possesses many other and advantageous features, some of which, together with the foregoing, will be set out more at length in the following description wherein will be outlined in full that form 35 of the invention which has been selected for illustration in the drawings accompanying and forming a part of the present specification.

The attached drawing which forms a part 40 of this application illustrates one of the preferred embodiments of the invention, wherein:

Figure 1 is a perspective view of the freezing can.

45 Figure 2 is a section thereof taken below the reinforcing band at the top.

Figure 3 is a sectional view of one of the sides, the conducting means and one of the reinforcing members taken on the line 3—3 50 of Figure 4, and

Figure 4 is a sectional view of a side of the can, of a conducting means and a reinforcing member.

In ice making apparatus, referring partic- 55 ularly to the container for forming cakes of ice, there has been employed a means for

conducting a fluid from the top of the can to the bottom thereof and allowing the exit of the fluid into the water to be congealed thereby keeping the impurities in the water 60 moving so that they will not be included in the resulting frozen cake of ice. Several means have been employed in order to conduct this fluid to the bottom of the can. It is advisable not to have the conducting means 65 or tube enter the freezing can but to have an opening in the side thereof through which the fluid may pass directly into the water to be congealed. By keeping the tubes on the outside of the cans they will not be injured during the process of freezing or by the removal of the ice cake from the can. In the practical use of these ice freezing cans, it is preferable to have a smooth interior 70 surface so that the ice will have a uniform shape and the ice cake will be easily removed from the can. If there are projections on the inner surfaces of the can extending into the can for varied distances, shoulders will be formed in the ice and will prevent the 75 cake from being easily removed.

The invention herein disclosed and described provides for a channel formed in one of the sides of the can and having such channel extend from the top toward the bottom of 85 the can, and having the fluid conduit assembled in this channel but not to extend into the can to form an indentation in the ice which will prevent the quick removal of the 90 ice from the can.

Referring to the figures, there is shown in Figure 1 the freezing can 1 which has the base 2 and the four sides. The top edge of the can is reinforced by a flange 3 which may be a separate piece attached to the 95 sides, or may be a continuous part of the sides turned back on themselves. Preferably, the freezing cans are made of metal but this invention is not limited to the material employed. A channel 4 is formed in one 100 of the sides so that a fluid conducting means or tube 5 may be assembled therein. This channel extends from the top of the side to substantially the bottom thereof. The channel may be formed in one of the shorter 105 sides so that the fluid may pass from the tube 5 across the longest part of the base of the can. It is to be understood that the channel may be in any one of the other sides of the can or may be in all four sides if desirable, and tubes assembled in such channel or channels. Channels without tubes may be 110

formed in any of the sides. The ice freezing can as herein disclosed is of the rectangular shape, but the invention is not limited thereto. However, if other designs of freezing cans are employed, it may be advisable to have the fluid directed across the longest distance between the sides at the bottom of the can.

The conducting means may be a tube or 10 pipe or any other fluid tight material of pipe construction. There is provided on the side in which the channel is formed, protecting members 6 which protect the tube and assist in maintaining it in normal position. A 15 general conception of the location of the channel and conducting tube is obtained from Figures 2 and 3, the latter showing more in detail the preferred design of the channel and tube. The channel 4 as shown 20 in Figure 3 is of the substantially semi-circular cross section and receives a tube 5 which is of circular cross section, but the designs of the channel and the tube may be varied to produce other desirable features, 25 and it is to be understood that this invention is not limited to the design illustrated. The tube 5 may be surrounded by a non-conductor of heat, if desired.

The formation of the lower end of the 30 channel and the contacting therewith of the tube or pipe is readily appreciated by reference to Figure 4 where the side 7 shows a portion of the channel 4 and the reception therein of the pipe 5. Since these freezing 35 cans are preferably made of metal, the metal may be readily pressed into various forms and the edge of the base 2 of the can in this instance is of U-shape form having the two upright portions 8 and 9. The center interior base portion 10 is generally higher from the floor or supporting member than the bottom edges of the U-shaped portion. The sides of the can are received by the U-shaped portion and are held in position by rivets 40 45 11. The channel in the side of the can terminates just above the plane of the base 10 and there forms a shoulder or end wall 12 through which an opening 13 is made. The opening 13 in the shoulder registers with the 50 natural opening 14 in the fluid conduit and such conduit is supported by shoulder 12, and it is not necessary to bend the pipe in any manner in order to assemble the same with the freezing can.

55 The formation of the channel 4 and the opening 13 therein may be formed at the same time as the stamping of the side from the sheet metal and by this method of manufacture there is a considerable reduction in

the production time required and the expense of labor. The pipe 5 can readily be assembled in the channel 4 and it is not necessary to fabricate the pipe in any manner as the opening 13 registers with the opening 14 of the pipe and the pipe may be 60 soldered onto the shoulder or may be attached thereto in any other desired manner. The pipe may also be soldered to the can at various points along its length. The upper 65 end of the pipe may have annular protruding beads to assist in holding a flexible hose connection to the pipe or, if desired, any other attaching means may be employed. The protecting pieces 6 assist in protecting the pipe and maintain the pipe in position. 70 These pieces may be spot welded in position or may be riveted or held by any other well-known attaching means. The opening 13 in channel 4 may be stamped therein at any desirable angle, the essential feature being that 75 it registers or coincides with the opening 14 of the pipe.

It will be understood that the embodiment of the invention herein described and shown in the accompanying drawings may be variously modified, and that the present invention is susceptible of different embodiments. In so far as such modifications and embodiments of the invention come within the scope of the following claim they are 85 considered to be within the scope of the invention.

I claim:

A freezing can having a channel formed vertically in one wall thereof, said channel 95 being of identical cross section from the top of the can to a point adjacent the base where said channel is provided with a perforated end wall forming an acute angle with the base and presenting a flat portion surrounding the perforation, a straight air tube mounted in said channel and extending from end to end thereof, the tube presenting an upper end open for connection with an air supply pipe and presenting a flat diagonal 100 lower end fitting against the corresponding flat portion of the end wall of the channel 105 around the perforation and soldered thereto to provide an air-tight conduit to the interior of the can, whereby air may be introduced into said can and directed across the bottom thereof to agitate the contained water during the freezing operation.

In testimony whereof, I have signed my name to this specification this fifth day of 115 November 1919.

ANSON J. BENTLEY.
